UNITED STATES PATENT OFFICE.

GERALD DEAKIN, OF LONDON, ENGLAND, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,393,630.

Specification of Letters Patent.

Patented Feb. 4, 1919.

Application filed August 16, 1917. Serial No. 186,654.

To all whom it may concern:

Be it known that I, GERALD DEAKIN, a citizen of the United States, residing at London, England, have invented certain new and useful Improvements in Telephone-Exchange Systems, of which the following is a full, clear, concise, and exact description.

This invention relates to telephone exchange systems employing machine switching of the type wherein a sensitive register is employed at the central office which is set by a sender manipulated by the calling party. When the register is so set power is automatically applied to the selector to drive it in a continuous movement to a point determined by the set register.

The object of the invention is to provide an improved automatic switching means for systems of this character.

20 Referring to the drawings in Figure 1 is shown diagrammatically, the physical structure of a selector switch. In Fig. 2 a connector switch is similarly shown. A section of the multi-coil electromagnet, operating 25 the stops, which in turn limit the vertical movement of the shaft, is shown in Fig. 3. Fig. 4 is a cross section of the air cylinder and piston, which operate the shaft. In Fig. 5 is shown a subscriber's line circuit 30 with its central office connections including the circuit of the distributor switch and of the master switch. In Figs. 6 and 7 are shown the selector and connector circuits respectively.

35 The selector switch indicated in Fig. 1 consists of a shaft 1, on which are mounted but insulated therefrom, three wipers 31a, 31b and 31c. The shaft, in its normal position, is capable of vertical and rotary motion in the order given and in the direction of the arrows. The wipers, upon the proper movement of the shaft as above indicated, are arranged to engage any one of a number of sets of fixed terminals, 32a, 32b and 32c, 40 generally called switch bank contacts. In the preferred form of my invention, each group of bank contacts (three groups being required to meet the circuit conditions), are arranged in ten rows of ten each. With such 45 an arrangement, the shaft may be required to assume any one of ten different vertical positions and the corresponding number of rotary positions. A reasonably air-tight cylinder 2 contains a piston 3, the latter being attached rigidly to shaft 1, which shaft is

arranged to slide through a hole in the top of cylinder 2 and through another in the center of disk 4. These holes act as bearings or guides to the shaft. Disk 4 is capable of rotary movement with the shaft by virtue of 50 key 1a, which is attached to the shaft, but not of vertical movement. Passage 5 normally closed by valve 7, leads to a source of compressed air. Outlet 6 normally opened by valve 7 acts as an exhaust outlet to air 55 chamber 8. B is an electromagnet controlling valve 7. When energized it causes valve 7 to close the exhaust outlet 6 and open the inlet 5, allowing compressed air to enter chamber 8. Shaft 1 is held by a spring or 60 otherwise (not shown) so that wipers tend to remain at the left of and below the switch banks. C is an electromagnet having ten concentric and adjacent windings, as shown in detail in Fig. 3. Each winding controls 65 a stop, D1 to D10. These stops do not normally interfere with the vertical movement of shaft 1. When, however, one of the magnet windings is energized, the corresponding stop is brought forward so as to engage the 70 shaft when the latter is moved vertically. In Fig. 1, stop D4 is shown in an operated position. The stops, for convenience in illustration, have been placed so as to engage the top of the shaft, the surface of the stops and 75 the top of the shaft being so shaped as to cause the shaft and wipers to be turned toward the right, in the direction of the arrow, when the two come into forced contact. The 80 construction and operation of the air chamber and piston is as follows: Upon energizing the valve controlling magnet B, air under pressure is allowed to enter chamber 8. This causes cylinder 3 to rise until the 85 top of shaft 1 engages a stop, which, in Fig. 90 1, would be stop D4. The shaft on striking the stop, is turned toward the right with the result that the air compressed in chamber 9 through opening 10 and normally prevented from passing through opening 11 by 95 the smooth side of cylinder 3 now passes through opening 11 and engages the piston vanes or blades 12, Fig. 4, which, being part of the piston 3, were brought opposite opening 11 by the turning of the shaft, the piston 100 now turns under the pressure of the air. The air traveling between the vanes and exhausting at 3a and 2a. As will be explained later on, release magnet Q, Fig. 1, controlling armature Q1, is energized during 105 rotation of the shaft, the piston 110

tion. Upon the selection of an idle trunk, this electromagnet is deenergized, thereby, and allows armature Q1 to return to its normal position and projection Q2 to engage a slot 13 on the periphery of disk 4, which was opposite Q2 at the moment of release. When the movement of piston 3 is stopped the pressure in the air chambers 8 and 9 is increased to the maximum. Under this condition, valve 14 operates against the tension of adjustable spring 15. The operation of this valve opens contact 16. At this point in the operation of the switch, valve controlling magnet B is deenergized, thereby allowing valve 7 to cut off the supply of compressed air and open the exhaust to air chambers 8 and 9. The switch is held in its operated position during a connection by armature Q1. To release the switch this armature is again attracted by electromagnet Q. The removal of the retaining finger Q2, from slot 13, allows the shaft to rotate back under the tension of the spring previously mentioned and then drop vertically to its normal position under the force of gravity or otherwise. Contact 17 is adapted to close whenever shaft 1 is moved out of its normal position, arm 18 being rigidly fixed to the shaft.

The switch shown in Fig. 2 is similar to that shown in Fig. 1, with the one important difference that the rotary as well as the vertical motion of the shaft is controlled by a series of stops. Corresponding parts are similarly numbered. This switch in its vertical movement of the shaft operates exactly as described in the previous paragraph. Upon reaching the predetermined level, the shaft is given a turn to the right in the usual manner, which causes the wipers to engage dead bank contacts 18, or their equivalent, the sole object of which is to retain the shaft in its vertical position when valve controlling magnet B is deenergized. The rotary movement of the switch is limited by stops F1 to F10, controlled by electromagnet E, having 10 windings E1 to E10. The construction of these stops is similar to those at C. The energization of any one of the 10 magnet windings would elevate a stop, which in turn would engage arm 19 attached to the periphery of disk 4a, and thus limit the movement of the shaft when the latter rotates. Contact 125 closes upon the initial rotary movement of the shaft.

Disk 4, Fig. 1, contains ten slots 13. Disk 4a in Fig. 2 contains eleven slots, 13. In each case the first tooth 13a, is beveled so as to permit stop Q2 or armature Q1 to be forced over this tooth into the first slot when the shaft is given its initial rotary movement, by striking a stop D1 to D10. With stop Q2, Fig. 1, in the first slot 13 on the periphery of disk 4, the wipers 31a, 31b and 31c would be in contact with terminals in the first vertical row of the switch banks 32a,

32b and 32c. With the stop in the next slot the wipers would be in contact with terminals in the next vertical row to the right and so on to the last vertical row. The arrangement of slots in the periphery of disk 4a, Fig. 2, are similar, the difference being that with stop Q2 in the first slot the wipers are in contact with the dead terminals 18 of the first row. The wipers do not come into actual contact with the switch banks proper until Q2 reaches the second slot.

The function of the selector or trunking switch, Fig. 1, is to select one of a number of groups of trunks corresponding to the digit called and then to automatically select the first idle trunk in that group.

The switch shown in Fig. 2 illustrates what is now well known as a connector; the function of this switch is to complete the last stage of any connection and it operates in response to the last two digits. In the particular form disclosed in the drawings the extent of the vertical motion is controlled by the next to the last digit and the rotary motion by the last digit.

The function of the third switch, herein called a distributor switch, is, as before stated, to hunt out the calling line and connect it to the selector associated with the distributor, there being one selector for each distributor. This latter switch, in the preferred form of my invention, has access to a bank of line contacts arranged in one continuous row instead of in horizontal and vertical rows, which is the arrangement of the banks for selector and connector switches, Figs. 1 and 2. By arranging the banks in one row the distributor is required to rotate or move in one direction only when selecting a line, and for the purpose of explanation, the distributor switch may be assumed to be of a type similar to the selector switch, Fig. 1, with those features pertaining to the vertical movement of the shaft omitted. Each distributor of this type would consist of a shaft and wipers, a cylinder adapted to rotate within an air chamber, a means of holding the shaft in its operated position, such as disk 4, and release coil Q of Fig. 1, a valve controlling magnet such as B, Fig. 1, adapted when operated to allow air to enter the air chamber and rotate the cylinder, and a relief valve such as 14, adapted to operate after the manner previously described when the movement of the cylinder is stopped, thereby causing the pressure in the air chamber to be increased to the maximum.

At G in Fig. 5 is shown a simple form of a subscriber's telephone circuit, consisting of transmitter G3, a receiver G4, a switchhook and contact G5, calling device contacts G6, adapted when operated to make and break the line circuit, a condenser G2 and a ringer G1. LP and LN are line conductors connecting the subscriber's station at G with

the central office at H. The line conductors terminate in two groups of switch or bank contacts. The first group of contacts H1, H2, etc., are distributor bank contacts, accessible to the distributor switches. The second group HH1, etc., are connector bank contacts, accessible to the connector switch. Associated with each subscriber's line is a cut-off relay H3, having two contact springs H4 and H5, the former adapted to remove, when relay H3 is energized, a ground from line conductor LP, and the latter a common lead to the master switch circuit J from conductor LN. With each group of subscribers' lines there is associated a master switch the circuit of which is shown at J. This circuit controls the distributor switches through master wipers J6 and J7 and master bank contacts J8 and J9, there being one set of bank contacts for each distributor switch. In a typical arrangement there would be approximately ten or fifteen distributor switches for each one hundred subscriber lines, the whole being served by one master switch circuit. Relay J2 is a quick acting relay in starting, but designed to be sluggish in releasing. This relay controls the motor-magnet J1, whose armature J4 engages the ratchet wheel J10 to which is attached, but insulated therefrom, wiper arms J6 and J7. Each energization of the master magnet J1 causes the master wipers to step ahead one set of contacts. Relay J3 is adapted to cause the master mechanism to continue to rotate should adjacent contacts be found busy.

The circuit of a distributor switch is shown at K. B' is the electromagnet controlling the air inlet valve which in turn controls the rotation of the shaft. Q is the release magnet which maintains the switch in an operated condition during the connection and releases it when the calling subscriber hangs up. Relay K' through a contact on relay O is connected to the negative wiper WN, which wiper is adapted to engage bank contacts such as LN1. O is a slow release relay. K' and K'' are quick acting relays. Contact 23^B is closed by the operation of a relief air valve, such as 14, Fig. 1. Contact 126 closes whenever the wiper shaft is moved out of its normal position. With each distributor switch is associated a selector switch. Conductors LP2, LN2 and L2 of Fig. 5 also appear in Fig. 6.

The circuit of the selector switch, Fig. 1, is shown in Fig. 6. C represents the multi-coil electromagnet controlling the shaft stops D1 to D10, shown in Fig. 1. B is the electromagnet controlling the air inlet valve and Q the release electromagnet. M' and O' are relays of the sluggish release type. Contacts 16 and 17 are controlled by the air relief valve and shaft respectively. W1, WP1 and WN1, are wipers adapted to engage

bank contacts L3, LP3 and LN3 respectively leading to the next switch. The impulse recording apparatus may be called the register, and operates in response to the impulses sent over the line conductors by the calling subscriber. Electromagnet R, which is in the line circuit, responds to each interruption of the line circuit by the calling device at the calling station and correspondingly rotates ratchet wheel 35 through its armature 40. To ratchet wheel 35 is fastened shaft 36. Attached to shaft 36, but insulated therefrom, is a wiper 37, adapted to engage bank contacts T1 to T10 when the shaft is rotated. An insulating stop or bushing 38 is also attached to the shaft. Slow acting relay S, in addition to opening contact 33 when energized, also attracts the armature of pawl 34 which holds the ratchet wheel in its operated position between impulses when R is momentarily deenergized. The insulating bushing 38 is arranged to allow contact 39 to close upon the first energization of electromagnet R. The adjustment between 40 and 41 is such that the contact does not break until just before the full movement of the armature. This contact is also closed again immediately after the electromagnet is deenergized and before the armature reaches its normal position. The object of this adjustment is to permit the closing of the local circuit through relay S and thereby cause the holding pawl of 34 to engage the ratchet wheel before the latter is removed from the control of the armature 40. It should be stated that shaft 36 is provided with a spring tending to cause it to resume its normal position.

Any number of switches arranged as indicated in Fig. 6 may be used in establishing a connection. All connections, however, must be completed by a connector, the circuit of which is shown in Fig. 7. Conductors L3, LP3, LN3, Fig. 6, may be connected with the corresponding conductors in Fig. 7.

In Fig. 7, the register operates in exactly the same manner as the register shown in Fig. 6. In the connector circuit, however, a second set of bank contacts T11 to T20 is provided. These contacts are connected to the multi-coil magnet E, which limits the rotary movement of the shaft. The multi-coil magnet C controlling the vertical movement of the shaft, is connected to contacts T1 to T10. B, Q'', O'' and M'' perform the same functions as B, Q, O' and M' in Fig. 6. U is a balanced bridged line relay and supplies current to the calling subscriber's line for the transmission of speech. 89, 90 and 91 are condensers of suitable capacity. Relay X in series with interrupter 118 supplies ringing current to the called subscriber's line relay. Relay Z applies a busy tone to the calling subscriber's line in case the called line is busy. Relay N oper-

ates when the called line is picked up by the connector, providing it is not busy. It controls the ringing relay X and the line relay AN. The switch wipers W2, WP2 and 5 WN2 are adapted to engage the terminals of the called subscriber's line such as P, LP1 and LN1, Fig. 5 at HH1. For the purpose of this description the same subscriber's line circuit, H, Fig. 5, may be treated as both the 10 calling and called line.

We may now proceed with the operation of the system, considering first the changes which take place when a subscriber removes his telephone from the hook switch to originate 15 a call.

The closing of the line circuit at switchhook G5, Fig. 5, establishes a circuit through the starting relay J2 of the associated master switch circuit J, the circuit extending 20 from earth 25, through battery 26, contact 43, winding of J2, contact H5, one side of line LN, calling device G6, switchhook G5, receiver G4, transmitter G3, the other side 25 of the line LP, H4 to earth 25. Relay J2 operates, closes contact between 44a and 44b and energizes the motor magnet J1, causing it to attract its armature J4 with a result that ratchet wheel J10 is turned one notch, causing wipers J7 and J6 to engage the next 30 set of bank contacts. The moment contact 44 a-b is closed and before armature J4 has broken contact 45, a ground is momentarily placed upon wiper J6 connected through bank contact J9 to the air inlet 35 valve controlling magnet B' of the distributor whose bank contacts J8 and J9 happen to be engaged by wipers J7 and J6 at the moment the call was originated. The closing of this momentary circuit from earth 40 25, through 44 a and b, 46 a and b, 45, J6, J9, winding of B', 26 to earth again at 25, causes B' to operate. Relay J2 as before stated is sluggish in releasing so that after being energized and opening contact 43, it 45 remains energized for a short time, the length of which is determined by the speed with which the distributors can be operated. It is intended that the interval of time during which contact 43 is open shall 50 be sufficient to permit a distributor to be started by the operation of a magnet B' and to select the calling line, at which time the cut-off relay H3 of that line is energized and connection between the calling line and 55 relay J2 broken at contact H5. By adjusting relay J2, in this manner, the wipers J6 and J7 will be allowed to engage the banks of the next distributor, but will not start that distributor on a hunt for a calling line, 60 since the ground necessary to start the distributor and normally on wiper J6, is removed at 45. Under the arrangement just described, when relay J2 again resumes its normal position and closes contact 43, it is 65 not again energized by the same calling line.

Therefore, the master wiper remains in the next position in readiness for the next call provided the next switch is not busy. Should the next distributor be engaged when wipers J6 and J7 are moved into contact with its 70 banks, wiper J7 will engage a grounded bank contact, the ground being supplied by the busy distributor K, Fig. 5, as will be explained later, from 25 at K, through shaft contact 126, 49, 48 to bank contact J8. A 75 circuit is now closed; through relay J3 from wiper J7, 47, winding of J3, 26, 25. Relay J3 when energized opens contacts 46 a-b and 47. The former releases motor magnet J1 and allows pawls associated 80 with armature J4 to engage the next notch on ratchet wheel J10. The local circuit through J8 is opened at 47 so that this relay tends to vibrate, and at each vibration the circuit of the motor magnet is opened 85 and closed, thereby causing the ratchet wheel to step ahead one notch. This vibration continues until a non-grounded bank contact J8 is found, at which time the circuit through relay J3 is opened. Even with relay J2 de- 90 energized wipers J6 and J7 cannot remain on busy contacts. Each time relay J3 is energized as just explained, motor J1 is operated, a circuit being established from 25 through 44a, 44c, 46c, 46a, winding of J1, 26 95 to 25.

We may now consider the operation of the distributor switch shown at K, Fig. 5. The energization of B', as explained in the preceding paragraph, opens the air inlet valve 100 which causes the switch wipers to rotate in their hunt for the calling subscriber's line, the wipers WP, WN and W engage a series 105 of fixed bank contacts such as LP1, LN1 and P, respectively. Upon the first movement of the shaft, contact 126 is closed and a circuit established through the release magnet Q', which permits the rotation of the shaft, a circuit being established from 25 through 126, 49, 50, 55, winding of Q', 26 110 to 25. The wipers in passing over idle lines find a ground on bank contacts LP1 through contact H4 of the cut-off relays H3, and battery on bank contacts LN1, through the common master switch relay J2 and the cut-off 115 contacts H5 of the cut-off relays. Normally the circuit of wiper WP is opened at 51. Wiper WN, however, is connected to battery through relay K' and contacts 53 and 54. Under the conditions just mentioned, 120 this relay does not operate. Furthermore, bank contact P of each non-busy line, is connected to battery through the winding of its associated cut-off relay. This contact, however, on engaged lines is grounded, the 125 ground extending from the first selector, as will be described later on, over conductor L2, to wiper W. Relay K" attached to circuit of wiper W is connected to battery through the closing of contact between 56 130

and 58 on B'. The switch wipers in their hunt for the calling line may, therefore, have to pass over two classes of lines, engaged lines and non-engaged lines. On 5 passing over non-engaged lines neither relays K' or K'' are energized. In passing over engaged lines, both relays K' and K'' are energized. The current through relay K' starts at the ground supplied by the 10 distributor to the positive side of the engaged line indicated at H by conductor LP1, and thence through the subscriber's telephone set back over the other side of the engaged line indicated by conductor LN, at 15 H, thence to the switch banks, at which point it divides, part extending to the other side of the connector circuit associated with the engaged line, and part through wiper WN, contact springs 53 and 54, winding of K' to 20 battery 26 and earth 25. The circuit through relay K'' originates with the ground found upon the engaged line bank contact P through wiper W, winding of K'', 58, 56, 26 to 25. The energization of relay 25 K' opens the circuit through the release coil Q', at the same time the circuit is closed by the energization of K''. In this way the switch is allowed to rotate by engaged lines. When the line of the calling subscriber is 30 found relay K' is energized, but not relay K'', there being no ground on bank contact P to energize the latter relay. Relay K' is energized by a current which may be traced from ground 25 at the cut-off relay 35 H3, through H4, LP, subscriber's set at G, back over conductor LN to LN1, at which point the current divides part passing through the master switch relay J2 and contact H5 and the remainder through wiper 40 WN, 53, 54, winding of K', 26 to 25. The energization of relay K' in this case opens the release coil Q', circuit at 55, and allows the stop controlled by this coil to engage a slot on the wiper shaft and retain the wipers 45 in contact with the switch banks LP1, LN1 and P of the calling subscriber's line. The stopping of the rotating mechanism causes the air relief valve previously referred to, to operate and close contact 23b. Relay Q is 50 now energized, a circuit being established from 25, through 126, 49, 50, 23b, winding of O, W, P, winding of H3, 26 to 25. The operation of relay O closes the line circuit from WP and WN to LP2 and LN2 respectively to the associated selector shown in 55 Fig. 6. The opening of contact between 49 and 50 deenergizes B'. The closing of contact between 48 and 49 places a ground upon the wire leading to the master switch bank 60 contact J8, and makes this distributor "busy" at the master switch. The ground which retains sluggish relay O and cut-off relay H3 in their energized positions, is supplied by the associated selector over 65 conductor L2 as will be described later.

The function of contact 23b is to give relays O and H3 their initial energization. This contact resumes its normal position when valve magnet B' is deenergized.

The distributor in its final position extends the calling line through to the selector, Fig. 6, placing electromagnet R, Fig. 6, of the register forming part of the selector, in series with the calling line, a circuit being established from earth 25, Fig. 6, through 70 one winding of R, 63, 64, conductor LP2, to distributor K, Fig. 5, through 51, WP, LP1, LP, through the substation G, back over the opposite side of the line LN, LN1, WN, 53, 52, conductor LN2, to the selector, 75 Fig. 6, 70, 71, the other winding of R, 26 to 25. The closing of this circuit energizes R, which attracts its armature 40, opening contact between 40 and 41 and causing ratchet wheel 35 to step ahead one notch 80 and in so doing turn shaft 36 a sufficient distance to close contact 39 but not sufficient to close contact between wiper 37 and bank contact T1. The register mechanism is so designed that a turn of the ratchet wheel 85 of two notches is required to close this circuit. Contact between 40 and 42 is also made. The result is that a ground is placed on the holding wire L2, from 25 through 39, 40, 42 to L2, thence over this conductor 90 to the distributor, Fig. 5, through winding of relay O, Fig. 5, 57, 56, 26 to 25. This ground also energizes the cut-off relay associated with the calling line as it forms a closed circuit from L2, through W, P, winding of H3 to battery 26 and earth 25. The energization of relay O maintains the distributor in its operated position. 100

We have now arrived at the point where the calling subscriber may proceed to send in impulses by manipulating the calling device, G6, Fig. 5, provided for the purpose. These impulses thus made are of short but equal duration. Relay S of the register in Fig. 6 is of a sluggish release type, such that contact 33 opened on the first impulse when R is momentarily deenergized, is not closed again until the impulses cease. At each impulse or interruption of the line circuit at G6, magnet R is deenergized and then reenergized with a result that ratchet wheel 35 is caused to step ahead one notch for each impulse. Similarly, wiper 37 is caused to step ahead one bank contact for each notch engaged by the pawl of armature 40. Upon the first deenergization of R, contact is closed between 40 and 41, thence through the winding of S, energizing the latter, which causes the pawl of armature 34 to engage ratchet wheel 35 and maintain this wheel in its operated position between impulses. Contact 33 is also opened by the energization of S. The circuit through S may be traced from earth 25, through 39, 40, 41, 72, winding of S, 67, 66, 110 115 120 125 130

26 to 25. At the end of a series of impulses, relay S is deenergized, due to the prolonged opening of its circuit between 40 and 41 and closes contact 33. The ratchet wheel 35 is 5 maintained in its operated position by armature 40, magnet R remaining energized between each series of impulses. Therefore, wiper 37 remains in contact with the particular bank contact selected in response to 10 the digit called. For example, in case the digit 8 were called, the eight impulses received by R would step wiper 37 into contact with T8. The result is that a circuit is closed from ground 25 through wiper 37, 15 T8, through winding C8 of the electro-magnet C, 33, B, 67, 66, 26 to 25, energizing both C8 and B. Stop D8, Fig. 1, thus caused to operate, engages the switch shaft which moves vertically when the air inlet 20 valve controlled by B is opened. The shaft upon striking the stop is turned to the right, giving the shaft a rotary movement, as previously explained. This preliminary rotary movement of the shaft causes wipers W1, 25 WP1 and WN1 to engage bank contacts L3, LP3 and LN3 respectively, of the first trunk in the group corresponding to the level or row to which wipers have been raised. Should this first trunk be busy, a ground 30 will be found upon bank contact L3, which ground will be transmitted by wiper W1 through 61, 60, winding of Q, 26 to 25. Q is now energized, which removes the holding stop from the disk on the switch shaft and 35 allows the latter to rotate under force of the air in a manner which has already been described. Bank contacts L3 of non-busy trunks are connected to battery instead of to ground. Therefore, when a non-busy 40 trunk is picked up by the rotating wipers, the circuit through Q is immediately opened. The deenergization of this coil allows the holding stop Q2 to return to its normal position and engage a slot 13 in disk 4, 45 Fig. 1, and thus maintain the wipers in contact with the terminals of the idle trunk. The stopping of the shaft causes an increase in air pressure which operates the valve opening contact 16, Fig. 6. The opening 50 of this contact removes a short circuit from the winding of relay M', thereby causing this relay to operate. Relay M' is now placed in series with relay O', which latter relay was energized when contacts 39 and 55 40—42 were first closed. Both relays remain energized until the calling subscriber hangs up. The operation of relay M' removes R from connection with the calling line and connects the latter straight through 60 to wipers WP1 and WN1, the transfer taking place at contacts 64, 63, 65 and at 70, 71 and 69. The opening of contact between 60 and 61 removes the winding of Q from connection with the wiper W1. The closing 65 of contact between 61 and 62 connects con- ductor L2 to wiper W1. The ground sustaining the connection is now supplied from the next switch over conductor L3, in the same manner that it was supplied to conductor L2 before relay M' was energized. 70 Contact 17 is controlled by the switch shaft and closes whenever the shaft is moved out of its normal position. The release circuit is opened at 73 during the connection. Air control contact 16 after opening again closes 75 when air pressure is reduced to normal, which takes place when contact is opened between 66 and 67. The opening of this contact releases B and C. The opening of contact between 66 and 68 removes the short 80 circuit from the winding of M' when contact 16 is again closed. The opening of the circuit through R allows armature 40 to resume its normal position and in so doing allows ratchet wheel 35 and wiper 37 to 85 return to their normal positions, at which time contact 39 is again opened. We now have a clean pair of wires from the calling subscriber's station through a distributor, a first selector to the next switch. In case 90 the connection is to be again trunked, a second, third and, if necessary, fourth selector may be used. The circuit of these additional trunking switches is the same as that of the first selector and for this reason need 95 not be described. As the connection proceeds the last switch added to the chain always holds the preceding switches busy. 100 Should the calling subscriber hang up after operating the first selector, he will open the line circuit and deenergize R of the register of the next switch. The deenergization of this magnet will remove ground from conductor L3, it being placed 105 on that conductor, as previously described, by the closing of a contact such as 39, Fig. 6. The removal of ground from conductor L3 allows relays O' and M' to release. The closing of contact 73 energizes the holding coil Q, which allows the switch to return to its normal position, the circuit being again 110 opened at 17 when the shaft reaches this position. The distributor is released at the same time by the deenergization of relay O, Fig. 5, the release circuit being established 115 through release coil Q' from 25 through 126, 49, 50, 55, winding of Q', 26 to 25. When this switch reaches its normal position, contact 126 is again opened. The removal of the ground from L2 also allows subscriber's 120 cut-off relay H3 to resume its normal position. 125 Should the calling subscriber hang up without operating the first selector, register relay S is released by the opening of its circuit at 72. If the circuit were not open at this point it will be seen that a circuit would exist through relay S from 39, through 40, 41, 72, winding of S, 67, 66, 26 to 25. Holding coil Q is always ener- 130

gized on a disconnection, whether or not impulses have been sent in, owing to the fact that contacts 39 and 40—42 are closed as soon as the selector is picked up by the calling line. Therefore, when relay O' is released by the opening of contact between 40 and 42, the circuit through release coil Q is closed at 73 through 40, 42 and 39 to ground.

- 10 The last stage of any call is always completed by a connector, the general physical arrangement of which is shown in Fig. 2 and its circuit in Fig. 7. As soon as the wipers of the preceding selector, Fig. 6, 15 engage the terminals of the trunk leading to the connector, Fig. 7, electromagnet R of the register of the connector is energized, a circuit being closed from ground 25, through one winding of R, 77, 78, conductor 20 LP3 to wiper WP1 of the selector, Fig. 6, 65, 64, conductor LP2 to the distributor (Fig. 5), 51, wiper WP, one side of the calling subscriber's line LP, through telephone set at G, back over the other side of 25 the subscriber's line LN, wiper WN, 53, 52, conductor LN2 to the selector (Fig. 6), 70, 69, wiper WN1, to conductor LN3, to the connector (Fig. 7), 84, 85, 106, the other winding of R, 26 to 25. The energization 30 of R places the ground on conductor L3 through 39, 40 and 42. The grounding of this conductor holds all preceding switches in their operated position by the energization of relays O, O', Figs. 5 and 6 respectively. Relay O'' of the connector is also energized, a circuit being established from grounded conductor L3 through the winding of O'', 82, 80, 26 to 25. The energization 35 of relay O'' opens contact 86 and prevents the energization of release coil Q'', which would otherwise take place, since the armature of O'' is grounded through the conductor terminating at contact 17.

The first series of impulses given the connector by the calling subscriber cause R to step ratchet wheel 35 and wiper 37 around to the proper bank contact T1 to T10. When the impulses cease, relay S resumes its normal position as previously described, 50 closing a circuit through the proper winding of the electromagnet C, the circuit being closed from grounded wiper 37, through the proper bank contact T1 to T10, through the proper winding of C, 21, 20, 110, winding of B, 109, 108, 26 to 25. This results 55 in the energization of the proper coil on C and the air inlet valve controlling magnet B. The opening of the air inlet valve causes the shaft to move vertically until it 60 engages the stop operated by C, at which time the shaft, as previously described, is given a preliminary turn to the right, causing the wipers to engage a dead bank contact 18, see Fig. 2. The shaft is held in 65 this position by the finger or stop Q2 on

armature Q1, which was forced over the beveled tooth 13^a, into the first slot 13 of disk 4^a, Fig. 2. Referring again to Fig. 7, the stopping of the shaft causes contacts 23 and 23^a, controlled by the air relief valve, to close. The contact closed by 23 operates relay Y. The operation of this relay does a number of things. It opens the circuit through electromagnet R at 106, relay S, valve controlling magnet B and 75 stop magnet C at 109. The result is that these magnets release, allowing ratchet wheel 35 and wipers 37 and 37^a to return to their normal position. Relay Y is made sluggish in resuming its normal position so 80 that ample time may be given for the release of the complete register. The closing of contact between 121 and 108 energizes relay AY; the circuit may be traced from 25, through 26, 108, 121, winding of AY, 85 17 to 25, contact 17 having been closed when the shaft was moved out of its normal position. Relay AY now locks up through contact 120, a circuit being established from 25 through 17, winding of AY, 120, 90 123, 95, 81, 80, 26 to 25. Armature 20 breaks contact with 21 and makes contact with 22. The switch is now in a position to receive the second and last series of impulses, originated when the last digit of 95 the wanted number is called. These impulses operate R and S in the usual manner. When the impulses cease, relay S again closes contact 110. A circuit is now established from grounded wiper 37^a, 100 through the proper bank contact T11 to T20, through the proper winding of rotary stop controlling magnet E, through one winding of Q'', 22, 20, 110, winding of B, 109, 108, 26 to 25. The result is that the 105 proper coil of E, Q'' and B are energized. The energization of B controlling the air inlet valve, causes the switch shaft to rotate. The energization of Q'' removes the holding stop from disk 4^a (Fig. 2) and 110 permits this disk to rotate. The energization of the proper winding of E operates the proper stop which limits the rotary motion of the switch. After the switch shaft has rotated and engaged the operated 115 stop, the air relief valve operates and again closes contacts 23 and 23^a, which in turn energize relay Y and thereby deenergize B, Q'', R, S and E. The deenergization of Q'' holds the switch in its operated position. Should the called line be busy, a 120 ground will be found upon bank contact P which will close a circuit through wiper W2, 75, 74, 101, 102, winding of Z, 23^a, 26 to 25. Z now operates and locks up through contact 94, a circuit being established from the grounded bank contact P through 75, 74, 101, 102, winding of Z, 94, 111, 26 to 125 25. The closing of contact 92 places a busy tone on one side of the calling line LP3, 130

through condenser 90. Lead 90a leads to a suitable busy tone transformer or other device. The opening of contact 93 prevents the energization of relay N. The switch 5 now remains in this position until the calling subscriber hangs up, there being no connection between the talking circuit of the called line branch of the connector and the calling line branch. When relay Y resumes 10 its normal position, electromagnet R is again placed in the calling line circuit and holds the connection busy through the contacts 40 and 42. During the interval in which the circuit of R is opened, the ground 15 removed from conductor L3 by the release of the ratchet wheel 35, thereby opening contact 39, is supplied by closing of contact 124 on relay Y. When the calling subscriber hangs up and opens the line circuit, 20 electromagnet R is deenergized. This removes the ground from conductor L3 by opening the contact between 40 and 42 and allows relays O'' Fig. 7, O' Fig. 6 and O Fig. 5 to release and in turn close the release 25 circuits of the connector, selector and distributor, thereby causing these switches to resume their normal positions. In Fig. 7 this is accomplished by the closing of contact 86. A circuit is thus established from 30 25 through the off-normal contact 17, 86, one winding of Q'', 26 to 25. The energization of the release magnet Q'' removes the holding mechanism and allows the switch shaft to return to its normal position, after 35 which the off-normal contact 17 is again opened. It also releases relay Z by opening its locking circuit at 111. The ground found upon bank contact P of the engaged subscriber's line may be supplied in one of 40 two ways. In case the engaged line originated the call, the ground would be supplied over wiper W of the associated distributor as already described. In case the engaged line answers the call, the ground 45 would be supplied by wiper W2 of the involved connector, as will be described later on.

Should the wanted subscriber's line be unengaged, bank contact P of the wanted subscribers' line will be found connected to battery through a cut-off relay, such as shown at H, Fig. 5. Therefore, relay Z will not operate when contact 23a is closed. Contact 93 remaining closed establishes a circuit 55 through relay N from ground 25 at N, through winding of N, 93, 125, 107, 108, 26 to 25. Relay N operates and locks up, a circuit being established from 25 through N, 98, 96, 111, 26 to 25. Contact 125 was closed 60 when the shaft was given the first rotary movement as previously explained. The closing of contact between 99 and 101 places a ground on the free end of one winding of line relay AN, the other end of which is

connected to one side of the wanted line 65 branch of the connector. The closing of contact between 96 and 97 places battery on free end of the other winding of line relay AN, the other end of which is connected to the opposite side of the called line branch of 70 the connector. The closing of contact between 100 and 101 places a ground upon wiper W2 through closed contact 74 and 75, with the result that the cut-off relay of the wanted subscriber's line is energized and 75 the called line freed from all battery and ground connections through the opening of the cut-off relay contact. The placing of ground upon wiper W2 also makes the connection busy to all other connectors. The 80 opening of contact between 95 and 123 releases relay AY. The closing of contact between 95 and 122 establishes a circuit through ringing relay X and the grounded interrupter 118, from ground 25 through interrupter 118, winding of X, 122, 95, 81, 80, 26 to 25. Relay X is thus caused to operate intermittently, the interrupter 118 being adapted to open and close the circuit. At 85 each energization of relay X, contact is 90 broken between 112 and 113 and between 116 and 117 and made between 113 and 114 and between 115 and 116. Ringing current is thus supplied from generator 119 to 95 wipers WP2 and WN2, thence over line conductors LP1 and LN1 to the called subscriber's station such as shown at G, Fig. 5. At this point the ringing current passes through condenser G2 and ringer G1 and 100 operates the ringer. The connector circuit remains in this condition until the called subscriber answers, at which time the calling line circuit is closed by switch hook G5, Fig. 5. A circuit is now established for a 105 flow of direct current through the called subscriber's telephone set. Therefore, during the next deenergization of relay X, current flows through line relay AN, a circuit being established from ground 25 on relay N, through 100, 101, 99, one winding of 110 AN, 112, 113, WP2, bank contact LP1, line conductor LP through the telephone set at G, back over line conductor LN to bank contact LN1, thence through wiper WN2, 116, 117 the other winding of relay AN, 97, 96, 115 111, 26 to 25. Relay AN is thus energized and closes contact between 105, 103 and 104. The closing of contact 103 and 105 energizes relay M'', which remains energized until the connection is released by the calling subscriber, it being placed in series with 120 relay O'' by the opening of contact between 80 and 82, which contact normally short-circuits its locking winding. Electromagnet R is removed from connection with the calling subscriber's line by the opening of contact between 84 and 85 and 77 and 78. The talking circuits of the called and calling line 125

branches of the connector are connected through the closing of contact between 78 and 79 and between 83 and 84. The closing of these contacts places line relay U in series with the calling subscriber's line. This relay is thus energized and in so doing closes contact 87, thereby grounding conductor L3 and holding the connection busy. The opening of contact between 74 and 75 and the closing of contact between 75 and 76 removes the control of the ground or wiper W2 from relay N to relay U. The closing of contact between 105 and 104 on relay AN short-circuits resistance 88 during conversation. When the called subscriber hangs up, relay AN is deenergized and thereby removes this short circuit from the resistance, which is thus placed in series with the calling line. The object of this resistance is to afford supervision to private exchanges and other special switchboards which may be associated with the calling subscriber's line. The deenergization of relay AN, however, does not release the connection. During conversation relay AN supplies current to the transmitter of the wanted subscriber's line and relay U to the transmitter of the calling subscriber's line, the high frequency voice current being transmitted from one line to the other through condensers 89 and 91. At the end of conversation the calling subscriber hangs up, opening the line circuit and deenergizing relay U. The ground is thus removed from conductor 13 by the opening of contact 87. Holding relays O'' of the connector, O' of the selector (Fig. 6) and O of the distributor (Fig. 5) are now deenergized, with the result that all switches are released and return to their normal position.

What is claimed is:

1. In a switch, the combination with a bank of terminals, a shaft having a brush, means for imparting a primary and secondary movement to said shaft to select first a group and then a terminal therein, of sets of mechanical stops for limiting the primary and secondary movements of said shaft, electromagnetic means for selectively positioning said stops, and a sender for controlling said means.
2. In a switch, the combination with a bank of terminals, a shaft having a brush, means for driving the same in one direction to select the group and in another to select a terminal therein, a set of mechanical stops for limiting the group choosing movement of the shaft, electromagnetic means including a sender for selectively positioning said stops, means for thereupon automatically actuating said driving means to cause said shaft to engage the positioned stop, said stop being constructed and arranged to deflect said shaft onto the first terminal in the se-

lected group, and means for arresting said brush upon one of the terminals of the group.

3. In a switch, the combination with a bank of terminals, a shaft having a brush, means for driving the same in one direction to select the group and in another to select a terminal therein, a set of mechanical stops for limiting the group choosing movement of the shaft, electromagnetic means including a sender for selectively positioning said stops, means for thereupon automatically actuating said driving means to cause said shaft to engage the positioned stop, said stop being constructed and arranged to deflect said shaft onto the first terminal in the selected group, and means for continuing the movement of the shaft and for arresting said brush upon one of the terminals of the group.

4. In a switch, the combination with a bank of terminals, a shaft having a brush arranged to select first a group and then a terminal therein by movements at an angle to each other, and means for driving said brush in a continuous movement to select first the group and then a terminal therein.

5. In a switch, an air chamber, a piston therein, means for admitting air into said chamber to drive said piston, means for stopping said piston, and a circuit changing device constructed and arranged to remain inoperative on the operating air pressure but to become operated on the increased air pressure as the piston is stopped.

6. In a switch, the combination with a bank of terminals, a shaft having a brush arranged to select first a group and then a terminal therein by movements at an angle to each other, a chamber, a piston therein connected to said shaft, and means for operating said piston to drive said brush in both its movements.

7. In a switch, the combination with a bank of terminals, a shaft having a brush arranged to select first a group and then a terminal therein by movements at an angle to each other, an air chamber, a piston therein connected to said shaft, and means for admitting compressed air to said chamber to drive said piston to actuate said shaft in both its movements.

8. In a switch, the combination with a bank of terminals, a shaft carrying a brush, a chamber, a member fitted in said chamber and connected to said shaft responsive to fluid pressure for imparting a rectilinear movement to said brush to select a group, said member being provided with vanes also responsive to fluid pressure for imparting to said brush a curvilinear movement to select a terminal therein.

9. In a switch, the combination with a bank of trunk terminals, a shaft having a

brush arranged to select first a trunk group and then an idle trunk herein by movements at an angle to each other, an air chamber, a piston therein connected to said shaft, means 5 for admitting compressed air to said chamber to drive said piston, a set of mechanical stops for limiting the group choosing movement of the shaft, electromagnetic means including a sender for selectively positioning 10 said stops, means for thereupon automatically actuating said driving means to cause said shaft to engage the positioned stop, said stop being constructed and arranged to deflect said shaft onto the first terminal 15 of the group whereupon the compressed air rotates the brush over the trunk group, means for stopping the brush on an idle trunk, and a circuit changing device operated by the increase in air pressure within 20 said air chamber when the piston is stopped.

10. In a telephone exchange system, the combination with telephone lines, a sender, an electrically operated registering device, a circuit including said sender and said device 25 whereby the same may be set, and a pneumatic switch thereupon automatically operated to interconnect said lines according to the set condition of said device.

11. In a telephone exchange system, the combination with telephone lines, a sender, 30 a register, a circuit including said sender and register whereby the same may be set, and a switch having a bank of terminals and a shaft carrying a brush adapted to choose first a group under control of said register and then a terminal therein by a continuous movement in two directions.

12. In a telephone exchange system, the combination with telephone lines, a sender, 40 a register, a circuit including said sender and register whereby the same may be set, a switch having a bank of terminals and a shaft carrying a brush adapted to choose first a group under control of said register and then a terminal therein by movements 45 at an angle to each other, and means for driving said brush in a continuous movement to said terminal.

13. In a telephone exchange system, the combination with telephone lines, a sender, 50 a register, a circuit including said sender and register whereby the same may be set and a switch having a bank of terminals and a shaft carrying a brush adapted to choose first a group and then a terminal therein by movements at an angle to each other under control of said register, and means for driving said brush in a continuous movement to the desired terminal.

60 14. In a telephone exchange system, the combination with telephone lines, a sender, a register, a circuit including said sender and register whereby the same may be set, a switch including a bank of terminals, and 65 a shaft having a brush adapted to choose

first a group and then a terminal therein by movements at right angles to each other under control of said register, said switch including a piston connected to said shaft and adapted to drive said brush in both its 70 movements.

15. In a telephone exchange system, the combination with subscribers' lines, a switch comprising a number of rows of terminals and a set of wipers, mechanical stops, subscriber controlled means for selectively actuating said stops, and a source of power for driving said wiper into engagement with the set stop, said stop and wiper being so constructed and arranged that the wiper is 80 thereby given a movement of translation to carry the same along the selected row.

16. In a telephone exchange system, the combination with subscribers' lines, a power driven switch having rows of terminals, 85 trunks terminating therein, a subscriber controlled means for selectively advancing said wiper into operative relation to the desired group and for imparting to said wiper a movement of translation over the group 90 without stopping the brush, and means for stopping the same on the first idle trunk.

17. In a switch, the combination with a bank of terminals, a shaft carrying a brush, a chamber, a member therein connected to 95 the shaft, a port for the admission of fluid pressure into said chamber for driving said member in a primary direction, a secondary port closed throughout the movement in the primary direction, and means operated at 100 the termination of the primary movement for automatically opening the said secondary port, said member being provided with vanes responsive to the admission of fluid pressure through said secondary port to impart a secondary movement to said brush.

18. In a switch, the combination with a bank of terminals, a shaft carrying a brush for selecting first a group and then a terminal therein, a chamber, a member therein 110 connected to said shaft, a primary port for the admission of fluid pressure into said chamber for driving said member in a primary direction, a set of stops for limiting the primary movement of the shaft, electromagnetic means including a sender for selectively positioning said stops, means for opening the primary port upon the setting of the stop, said secondary port being closed during the primary movement by a part of 115 said member, said stop being constructed and arranged to deflect the brush onto the first terminal of the selected group whereby said member opens said secondary port vanes being provided on the member responsive to the admission of fluid pressure through said secondary port to impart a secondary movement to said brush to select a terminal in the selected group.

19. In a telephone system, an automatic 120

switch including an element movable in two intersecting planes, means for moving said element by a single continuous motion in both directions, step-by-step means for controlling the extent of operation of said movable element and circuits for controlling said operation.

20. In a telephone system, an automatic switch including a movable element, means for moving said element by a single continuous motion in two directions, and step-by-step means controlled over the two sides of a metallic talking circuit in series for controlling the extent of operation of said movable element.

21. In a telephone system, a subscriber's line, an automatic switch including arms movable in two intersecting planes, means on said subscriber's line for transmitting a varied number of impulses to control said switch, means for moving said arms by a single continuous motion in both directions, and means controlled by said varying number of impulses for controlling the extent of motion of said arms.

22. In a telephone system, a subscriber's line, an automatic switch including movable arms, means on said subscriber's line for transmitting a varied number of impulses over the two sides of a metallic talking circuit in series to control said switch, means for moving said arms by a single continuous motion in two directions, and means controlled by said varying number of impulses for controlling the extent of motion of said arms.

23. In a telephone system, an automatic switch including movable arms, means for moving said arms by a single continuous motion in two intersecting planes, step-by-step means for controlling the extent of motion of said movable arms and circuits for controlling said operation.

24. In a telephone system, an automatic switch including movable arms, means for moving said arms by a single continuous motion in two intersecting planes and a step-by-step means controlled over a metallic cir-

cuit for controlling the extent of motion of said movable arms.

25. In a telephone system, an automatic switch including movable arms, means for moving said arms by a vertical motion, means for controlling the extent of said vertical motion, means for rotating said arms and means whereby said vertical motion is translated without pause into said rotary motion, and circuits for controlling said operation.

26. In a telephone system, an automatic switch including an operating shaft, means for controlling the operation of said shaft in two directions through a single continuous motion and means for simultaneously operating said controlling means at one speed and said operating shaft at a second speed.

27. In a telephone system, an automatic switch including a movable element having motion in two intersecting planes, a single operating means for moving said element in both of said planes, means for causing the movement of said element in said two planes to be continuous and electrical circuits for controlling said operating means.

28. In a telephone system, an automatic switch including a movable element having motion in two intersecting planes, a single operating means for moving said element in both of said planes, means for merging said two movements in different directions into a single movement, and means for controlling said operating means over a metallic circuit.

29. In a telephone system, lines divided into groups, an automatic switch including a movable element having motion in one plane to select groups and motion in a plane at right angles thereto to find a line in the selected group, a single operating means for moving said element in both of said planes and means for causing the two movements to merge into a single continuous movement.

In witness whereof, I hereunto subscribe my name this 19th day of July A. D., 1917.

GERALD DEAKIN.
